UNITED STATES PATENT OFFICE

HENRY W. COOPER, OF WEST NEWTON, MASSACHUSETTS, ASSIGNOR TO NEW ENGLAND MICA CO., OF WALTHAM, MASSACHUSETTS, A CORPORATION OF MASSACHUSETTS

METHOD OF MANUFACTURING COMPOSITE SHEETS

Application filed November 3, 1927. Serial No. 230,892.

The present invention relates to the manufacture of composite sheets of flake material and especially to the production of manufactured mica plate consisting of stratified mica films used in insulating electrical apparatus.

In one of its aspects, the invention consists in a novel method in accordance with which the constituent flakes of the required sheet are completely assembled in a dry condition, then immersed in a bath of liquid adhesive and finally solidified by pressure to form a sheet. This method has been developed with satisfactory results to a point where it produces stratified mica plate more readily, at less expense and with a smaller consumption of adhesive than has been possible by the methods heretofore known.

In practicing the method of my invention, it has been found desirable to retain the assembly of dry flakes against displacement while it is being permeated or otherwise treated with the adhesive. Preferably, therefore, I include in the method the step of engaging and retaining the assembled flakes against displacement on their supporting surface while they are carried through a bath of liquid adhesive.

Another important step, which I also prefer to include in practicing my novel method, consists in solidifying the cohered flakes into sheet form by pressure applied while the assembly remains engaged and retained against displacement.

The disclosure herein includes an improved machine by which the method above described may be practiced in an advantageous manner. As herein shown, the machine comprises a conveyor upon which flakes of mica or the like may be assembled, a traveling apron for progressively engaging the assembled flakes and retaining them against displacement on the conveyor, and a bath of liquid adhesive disposed in the path of the conveyor and apron and in which the assembled flakes may be immersed while held in position between the conveyor and apron.

As above stated, it has been found desirable to solidify the cohered assembly of flakes while retained against displacement upon

the conveyor whereon they have been assembled. To this end, another feature of the machine consists in pressure rolls so designed and located as to engage the conveyor and apron as they emerge from the adhesive bath carrying the cohered flakes and to press the two together to solidify the sheet material between them.

The novel method and the construction of the machine by which the method may be practised will be best understood and appreciated from the following description of a preferred embodiment of the machine, selected for purposes of illustration and shown in the accompanying drawings, in which

Fig. 1 is a view in side elevation of the portion of the machine for applying adhesive to the flakes carried by the conveyor and compressing them into a sheet;

Fig. 2 is a sectional view of the same portion of the machine;

Fig. 3 is a plan view of the same portion of the machine; and

Fig. 4 is a view in side elevation, on a reduced scale, showing more or less diagrammatically the entire machine up to the inspection table.

The machine comprises an elongated frame upon which the different mechanisms of the machine are assembled. These comprise an endless conveyor extending the full length of the frame, bins and sifting mechanism located at one end of the frame for supplying mica flakes to the conveyor, a tank and associated mechanism for applying liquid adhesive to the flakes showered on the conveyor, and means for compressing and compacting the cohered flakes into an integral sheet.

These elements of the machine will be described in the order in which they have been enumerated. The main frame of the machine is built up of pairs of angle iron posts or legs 22, connected by cross bars, not shown, and by long horizontal side bars 21. The conveyor is made up of a pair of spaced sprocket chains 24 to which are connected the edges of a web of foraminous material, preferably a wire mesh cloth 25 having about four meshes to the inch. The chains of the conveyor are supported and driven by a series of

sprocket wheels 26 carried by transverse shafts 28 journaled in the main frame of the machine and each carrying a worm wheel 30, meshing with a worm 32 mounted upon a shaft 34 extending longitudinally for the whole length of the frame and journaled in boxes 36 carried by the legs 22 thereof. The shaft 34 is driven from any convenient source of power, not shown, and acts to drive all of the sprocket wheels 26 in a counter clockwise direction, so as to advance the upper pass of the conveyor from right to left, as seen in the drawings. The lower pass of the conveyor is supported by idle rolls 251 journaled between each pair of legs 22.

At the right-hand end of the frame and above the conveyor is located a number of bins 40, two of which only are shown in Fig. 4. Each of the bins contains two oscillating cradles 42 with perforated walls of expanded metal, having openings of appropriate dimensions and adapted in their oscillation to sift out and shower mica flakes upon the conveyor passing beneath them. The flakes are supplied in bulk to these cradles through suitable ducts 44 extending into the bins 40 from a source of supply, not shown. Each of the cradles is carried by a transverse shaft 43, having a toothed segment 46 at one end, meshing with a horizontally disposed reciprocating rack 48 guided by spaced pairs of rollers 49 and actuated from a crank disc 51 through a connecting rod 53. The crank disc is carried by a transverse shaft 55, driven by a belt 57 from a motor 59 or other convenient source of power. Clutch mechanism, controlled by a handle 47, is provided for throwing each cradle into or out of operation in accordance with the requirements of the work in hand.

The mechanism above described is indicated in Fig. 4 diagrammatically rather than structurally but it will be apparent that the conveyor, in traveling toward the left beneath the bins 40, accumulates a layer of mica flakes which is increased in thickness as it progresses into the range of each of the cradles 42. On account of the foraminous nature of the conveyor, dust and flakes of insufficient size for the required purpose are sifted out of the lower layer of the flakes, so that only flakes larger than the mesh of the conveyor are carried away from the first bin. The action of the cradles and their rate of supply is so controlled that the layer of flakes, as it passes from the left-hand bin of the series, is built up to the required thickness and constitutes a loose, dry assembly of material before the operation of binding the flakes together takes place.

Figs. 1, 2 and 3 illustrate in somewhat greater structural detail that portion of the machine wherein adhesive is supplied to the layer of flakes assembled on the conveyor in the manner above set forth. The main frame

of the machine carries an elongated tank 50, located to the left of the last bin 40 of the series and in such position that the conveyor can be deflected into the adhesive 52 which the tank contains, which may be shellac or any other suitable liquid binder. To this end, guide rollers 54 are provided which lead the conveyor to the wall of the tank 50, then deflect it downwardly below the surface of the shellac and finally guide it back into its original path as it leaves the tank. The rollers 54 are journaled in the side bars 21 and provided with sprocket wheels at each end which mesh with the chains of the conveyor so that the rollers are driven at the same surface speed as the conveyor.

In order to prevent displacement or floating away of the mica flakes as these are carried into the shellac by the conveyor, provision is made for engaging the flakes at the exposed face of the layer and holding them in place upon the foraminous web 25. This is effected by an endless apron of wire mesh cloth 60, which is guided into engagement with the upper surface of the layer of mica flakes on the conveyor web as the latter enters the tank 50. For this purpose, a series of three drums 62, 63 and 64 is provided for driving and guiding the apron 60 in the desired path. The drum 62 is carried by a transverse shaft 65, journaled in suitable shaft hangers 66, bolted to the side rails 21 of the frame and carrying sprocket wheels 68 at its outer ends which mesh with and are driven by the sprocket chains of the conveyor. The drum 64 is similarly mounted upon a shaft 67, journaled in hangers 69, and is similarly driven by the conveyor chains through the sprocket wheels 71. The drum 64 serves to guide the apron 60 into contact with the material on the conveyor web 25, automatically and progressively covering said material.

The center roll 63 is an idle roll and is constructed and arranged to maintain suitable yielding tension upon the apron 60. To this end, it is journaled in sliding boxes 70, mounted for vertical movement in slotted hangers 72, secured to the rail 21, and having its weight compensated to some extent by compression springs 74 disposed beneath the boxes.

The apron 60 is maintained in contact with the conveyor web 25 throughout the course of its travel in the shellac bath 52 and until after it has emerged therefrom. The roller 54, located at the left end of the tank 50, cooperates with presser roller 80 for pressing, compacting and solidifying the adhesive permeated layer of mica flakes as it is carried out of the shellac bath between the conveyor web 25 and the apron 60 and also for stripping surplus shellac from the sheet, so that it may be returned to the tank. The roller 80 is carried by a shaft 82, journaled in boxes 150

84, mounted in a pair of slotted hangers 86, secured to the side rails 21 of the frame. Each box is urged upwardly by a compression spring located beneath it but may be 5 moved downwardly to exert a predetermined but controllable amount of pressure upon the layer of mica by a hand screw 88 provided for that purpose.

As the solidified mica sheet 90 is carried beyond the drum 62, the apron 60 is stripped from it and the sheet is carried forward, exposed upon the conveyor where it may be conveniently inspected and eventually cut into smaller sheets of commercial sizes.

15 In my co-pending application Serial No. 230,891 filed of even date herewith I have shown a complete mica plate laying machine, including a light table for inspection and rectification of the sheet, of the same general design as is partially illustrated by Fig. 4 of this application but differing therefrom in that means is provided for applying adhesive binder to each layer of the mica flakes as they are successively showered upon the conveyor. 20 25 The herein illustrated machine, for practising the method of supplying binder at one operation to a dry assembly of the mica flakes as claimed herein, may be substituted in the machine of my co-pending application for the mechanisms employed for effecting said step-by-step application of the binder with a saving of the binder and an increased dielectric strength in the finished plate. Accordingly generic claims to the complete machine 30 35 and method of manufacture will be found in my co-pending application Serial No. 230,891, the claims of this application being confined to the alternative method of supplying the binder.

40 The steps of the method of my invention as carried out in connection with the machine disclosed will be apparent from the foregoing description but may be briefly stated as follows. The constituent mica flakes are assembled to the desired thickness upon the surface of the conveyor as it passes beneath the bins 40. This dry material is then automatically and progressively engaged and retained against displacement by the apron 60. 45 50 While so retained, it is carried through the adhesive bath in the tank 50 and before being released or uncovered is compressed into an integral or coherent sheet by the pressure rolls 54 and 80. The sheet 90 thus formed is then uncovered by the apron 60 and is ready 55 for further treatment in its manufactured form.

It will be apparent that the machine herein disclosed may be used to good advantage for carrying out the method of my invention, but such method is not in any sense dependent upon this or any particular machine construction but may be practiced in connection with any apparatus suitable for its various steps. 60 65 In a divisional application Serial No. 386,052

filed August 15, 1929 I have claimed the machine illustrated and described herein.

Having thus described my invention, what I claim as new and desire to secure by Letters Patent is:

1. The method of making composite sheets which consists in assembling the constituent flakes for the required sheet, retaining the assembled flakes against relative displacement, permeating the flakes with adhesive 70 while so retained, and, without releasing the cohered flakes, solidifying them by pressure to form an integral sheet.

2. The method of making composite sheets which consists in assembling the constituent flakes upon a movable surface, holding the material thus collected against displacement upon said surface, immersing the assembled flakes in a bath of liquid adhesive while so held, and then solidifying the cohered mass 75 80 85 to form an integral sheet.

3. The method of making composite sheets which consists in showering the constituent flakes upon a supporting surface forming a 90 complete, dry, loose assembly for the required sheet, immersing the material thus collected with its supporting surface in a bath of liquid adhesive, and then removing surplus adhesive and solidifying the sheet by pressure.

4. The method of making composite sheets which consists in showering the constituent flakes upon a movable surface, forming progressively a complete, dry, loose assembly for the required sheet, progressively immersing the material thus collected with its supporting surface in a bath of liquid adhesive, and then removing surplus adhesive and solidifying the sheet by pressure. 95 100

5. The method of making composite sheets upon a traveling conveyor which consists in assembling the constituent flakes upon said conveyor, retaining said flakes against relative displacement by pressure, leading them, while so retained, through a bath of liquid adhesive and, without releasing such retaining pressure, subjecting the adhesive permeated mass to a further solidifying pressure. 105 110

6. The method of manufacturing an endless sheet of stratified mica films which comprises continuously producing a layer of mica films of substantially uniform thickness, progressively engaging said layer between foraminous coverings and passing the covered layer through a bath of liquid binder, and then solidifying the layer by pressure. 115 120

7. The method of manufacturing a plate of stratified mica films which comprises building up a layer of dry mica films to the desired thickness, and immersing said layer of mica films in a bath of liquid binder while holding the layer between coverings of foraminous material to retain the films against relative displacement while permitting the binder to permeate through the layer. 125

8. The method of manufacturing a plate of 130

stratified mica films which comprises building up a layer of dry mica films to the desired thickness, immersing said layer of mica films in a bath of liquid binder while holding the layer between coverings of foraminous material to retain the films against relative displacement while permitting the binder to permeate through the layer, and then subjecting the layer to pressure while still between said coverings.
